UNITED STATES PATENT OFFICE.

GEORGE F. HAUSERMAN, OF BARTOW, FLORIDA.

DRIER.

Application filed December 30, 1921. Serial No. 525,835.

To all whom it may concern:

Be it known that I, GEORGE F. HAUSERMAN, a citizen of the United States, residing at Bartow, in the county of Polk and State 5 of Florida, have invented new and useful Improvements in Driers, of which the following is a specification.

This invention relates to improvements in drying kilns, the general object of the 10 invention being to so construct the kiln that the maximum amount of drying space is secured and the material will be more evenly dried than in kilns as now constructed.

15 This invention also consists in certain other features of construction and in the combination and arrangement of the several parts, to be hereinafter fully described, illustrated in the accompanying drawings 20 and specifically pointed out in the appended claims.

In describing my invention in detail, reference will be had to the accompanying drawings wherein like characters denote like or 25 corresponding parts throughout the several views, and in which:—

Figure 1 is an elevation of the improved kiln.

Figure 2 is a plan view thereof.

30 Figure 3 is a longitudinal sectional view through one end thereof.

Figure 4 is a similar view through the opposite end.

Figure 5 is a section on line 5—5 of Figure 35 4.

Figure 6 is an enlarged plan view of the front end of the apparatus with parts broken away.

Figure 7 is a fragmentary sectional view 40 of the front door 2.

Figure 8 is a detail sectional view showing the means for holding the door in raised position.

Figure 9 is a perspective view of the door.

45 In these views 1 indicates the drying room which extends from end to end of the building, access to the room being provided by the doors 2 which are provided with horizontal hinges at the upper ends, as shown at 50 3. These doors swing outwardly. The doors are adapted to be actuated by means of a winch 4 and the cables 5 which pass over the guiding pulleys 6. Each cable is connected with a door so that when the winch 55 is operated the doors will be swung to open or closed position. Each cable is provided

with a ring 7 which is adapted to engage a hook 8 so that the doors can be held in raised position and the cables released from the winch. This will permit the winch to 60 be used for pulling the trucks 9 into and out of the drying room by means of the cables 10 which are connected with the winch after the door operating cables are released therefrom. At the front end of the building 65 a chamber 11 is formed which is located above the drying room and this chamber contains the heating coils 12. This chamber is provided with a cold air intake 13 which is controlled by the shutter 14. The bottom 70 of the chamber is provided with an opening 15, at its front end, which is in communication with the front end of the drying room so that the heated air will pass from the chamber 11 into the drying room to come 75 in contact with the veneer or other material to be dried. In order to direct this air to the bottom of the drying chamber I locate a flue 16 on the front door, which, when the door is closed, will cover the opening 80 15 so that the air passing through the same will escape from the flue near the bottom of the drying room.

A fan chamber 17 is located above the drying room at the rear end thereof and this 85 chamber is in communication with the drying room by means of the passage 18. A fan 19 is arranged in the chamber 17 so that when the fan is actuated a suction will be created to draw the air from the drying 90 room into the chamber and this air will discharge through the outlet 19'. The fan may be actuated in any desired manner, the drawings showing a pulley 20 on the fan shaft 21. The chamber 17 is provided with 95 a damper 22 in front of the fan which acts as a means for preventing a vacuum being formed in the apparatus when the cold air damper is partly closed.

By my arrangement of parts the entire 100 space within the drying room can be utilized for drying the material. By placing the heating coils and the fan above the drying room the trucks can enter the room from the ends thereof and the size of the building can be reduced. By introducing the air into the 105 drying room at the bottom thereof a better drying effect is secured as the heated air travels along the floor in the space between the loaded trucks and the floor and passes up through the racked material on the trucks and thus dries the material evenly. The 110

damper 14 can regulate the heat and when this damper is nearly closed damper 22 can be opened so as to reduce the strain on the fan.

5 It is thought from the foregoing description that the advantages and novel features of my invention will be readily apparent.

I desire it to be understood that I may make changes in the construction and in 10 the combination and arrangement of the several parts, provided that such changes fall within the scope of the appended claims.

What I claim is:—

1. A kiln of the class described comprising a drying room, a heating chamber above 15 the same and connected with the front end thereof, a suction chamber above the dry-

ing room and connected with the rear end thereof and means directing the heated air from the heating chamber to the lower part 20 of the drying room.

2. A kiln of the class described comprising a drying room, a heating chamber located above the same and connected with the front end thereof, means for controlling 25 the entrance of cold air to said heating chamber, a suction chamber above the drying room and connected with the rear end thereof, means for placing the suction chamber in communication with the atmosphere doors at 20 the ends of the drying room and means for actuating the doors.

In testimony whereof I affix my signature.
GEORGE F. HAUSERMAN.
